Primary Examiner — T. Chase Nelson(74) *Attorney, Agent, or Firm* — Thompson Coburn LLP;
 Alan Norman(57) **CLAIM**

The ornamental design for a shoe midsole, as shown and described.

DESCRIPTION

FIG. 1 is a perspective view of a shoe midsole showing the new design;

FIG. 2 is a lateral side elevational view thereof;

FIG. 3 is a medial side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines are for the purpose of illustrating environmental structure; the broken lines form no part of the claimed design.
